BEDFRAME LEG

Melvin E. Roche, Strongsville, Ohio, assignor to The Harvard Manufacturing Company, Cleveland, Ohio, a corporation of Ohio

Application December 9, 1954, Serial No. 33,468

Term of patent 14 years

(Cl. D5—2)

FIG. 1

FIG. 3

FIG. 2

Fig. 1 is a front perspective view of a bedframe leg, showing my new design;

Fig. 2 is a rear or inner view in perspective; and

Fig. 3 is a side elevation.

I claim:

The ornamental design for a bedframe leg, substantially as shown.
